HYDRAULIC SYSTEM AND METHOD.

1,311,861.

Specification of Letters Patent. Patented July 29, 1919.

Application filed April 15, 1916. Serial No. 91,449.

To all whom it may concern:

Be it known that I, GEORGE G. EARL, a citizen of the United States, residing at New Orleans, in the parish of Orleans and State 5 of Louisiana, have invented certain new and useful Improvements in Hydraulic Systems and Methods; and I do hereby declare the following to be a full, clear, and exact description of the invention, such as will enable others skilled in the art to which it 10 pertains to make and use the same.

My invention relates to improvements in hydraulic systems, hydraulic apparatus and methods, and more particularly to improvements which relate to and are intended to produce proportional flows for the actuation 15 of apparatus, such as meters or other equipment. I also aim to improve the regulation of fluid pressure or fluid flows employed to control or operate such equipment.

Certain objects, advantages and uses of my invention, as well as the invention itself will be better understood from and with a 20 description of an embodiment of my invention.

The figure illustrates a fluid system constituting an embodiment of my invention and serving to illustrate a method constituting an embodiment of my invention.

The figure illustrates an application of my invention, and one of many forms in which I contemplate using it in practice. In general, a small Venturi tube is shown connected between the throat and the approach 30 chambers of a large venturi. A source of fluid and fluid pressure is shown at 40, connected through a duct 41 to a water main 42. A large venturi, shown at 120, is connected in the main 42. A small venturi 115 35 is connected from the approach chamber 113 to the throat chamber 114 of the venturi 120. In this arrangement it is preferable to use more and larger piezometer holes connecting into the throat and the approach 40 chambers of the large venturi than would be used if pressures only were to be taken from said chambers. I may also use larger chambers, as illustrated at 43 and 44. As a result, the amount of flow which the small 45 venturi will pass will meet its main resistance in its passage through said small venturi. In such an arrangement the venturi head in the large venturi will be, say as

illustrated at h , and ascertained through the piezometer tubes 45 and 46. This h represents the total loss of pressure for the small venturi resulting in the flow therethrough which such total loss of head produces, and due to this flow in a venturi head h_1 , on the small venturi, several times greater than the venturi head h on the large venturi. In this case, the pressure difference intensifier applied to an ordinary dimension of venturi permits it to operate accurately to much lower quantities of flow, or if the desired range of flow is not great, it permits of a larger relative throat area in the large venturi, and, therefore, of a greatly reduced loss of head in said large venturi.

I have also shown forms of means and method for utilizing the pressure difference intensifier. A proportional flow is withdrawn from the approach chamber 43 at the approach 113 of the venturi 120, escaping through the duct 50, where it passes through the orifice 116 into a cell 51' of a chamber 52, which contains a movable member 117, preferably what is known as an equal pressure diaphragm, which will maintain a pressure difference on the orifice 116 of either h or h_1 , depending upon whether the pressure of the main throat 114 or the intensifier throat 115 is permitted to act in the pressure cell 51', the pipes 115' and 114' being alternates, either of which can be used and the other closed, a gate valve 154 being employed in the pipe 114' and a gate valve 155 being employed in the pipe 115'.

A duct 60 conveys fluid to the throttling valve 118, which valve is connected by a 90 stem 61 to the movable member 117. The movable member 117 will move in accordance with the pressure differences in the main, according to a well known hydraulic law, and so operate the valve 118 as to permit a fluid flow through the duct 119, proportional to the flow through the main. When it is desired to record very low values of h , there finally comes a point where the friction of the valve 118 and the unbalancing 95 effect of the flow through its parts, although very small as compared with the power of any pressure difference whatever on the diaphragm 117, is nevertheless a source of some error, because at low flows very small pressure increments indicate material flow in 100 105

crements. Now, by connecting the chamber 52 with the intensifier throat 115, instead of with the main venturi throat 114, I obtain the pressure difference h' on the orifice 116, instead of the pressure difference h , which is several times larger than h , and the resistance and unbalancing effect above referred to, being practically constant and very small in amount of pressure difference 10 which they will permit on the two sides of the diaphragm 117, the error from the true pressure difference required for proportional discharge on orifice 116 is negligible for a much reduced velocity in the main throat 15 114 when the orifice is working under the pressure h_1 than when it is working under the pressure h . By using the intensifier pressure difference h_1 in the pressure chamber 52 and a reasonably large diaphragm 117, the throttling valve 118 will maintain the head h_1 on the orifice 116 for velocities in the throat 114 20 which are very far lower than could otherwise be operated with.

25 The proportional discharge from the valve 118 escapes, as I have explained, through the pipe 119 under adequate pressure to permit of the indication of its rate of flow by the manometer M, which shows the pressure difference on the orifice O, also of its integration by the meter 121 and the recording of its flow by means of the heart-shaped eccentric 123 carried by the wheel 122, which is driven by the meter 121, and which in turn actuates the pen 125 to draw the M-shaped line on the clock driven recording device 126, whose position with reference to the vertical time lines and the horizontal quantity lines at all times and positions shows the quantity of flow which has passed 30 35 40 the meter between any given time intervals.

On the wheel 122 are projections 124, which operate to cause a four-way valve piston 128 to reciprocate against the spring 128', thus introducing pressure from the 45 pipe 127 connected to a source of fluid pressure 70 and permitting waste through the pipe 127'. The pressure is introduced alternately through the pipes 129 and 130 into a cylinder 71 on opposite sides of the piston 50 133, and causes the said piston to reciprocate whenever a projection 124 passes the stem of the valve piston 128. The reciprocation of the piston 133 causes a slide 137 to reciprocate also, thereby causing the 55 pockets 134 to be alternately filled from the container 132 and emptied through the openings 135 into the receptacle 136, and thereby causing a quantity of a substance proportional to the flow of fluid in the main 42 to 60 be removed from the container 132 to the receptacle 136.

The portion of the drawing which I have so far described, when it is desired to govern a large flow or to absorb a very large amount of pressure at the governing throttle 118 or

make the leakage of flow very small when the throttle is closed, may not be accurate enough for all purposes, owing to friction or tightness in the valve piston of the valve 118, and the tendency, due to throttling, to cause an unbalanced action at the proportional throttling valve 118. I have shown means which in such event can be employed, to overcome any inaccuracies resulting from these or other causes. In the embodiment 70 illustrated, this device is shown generally at 165 and consists of a casing 166 in which there are mounted two diaphragms shown at 140 and 141, whose edges are associated 75 with the casing in such a way as to divide the casing into a plurality of chambers 167, 168 and 169. The diaphragms 140 and 141 may be of any desired relative area and weighted as desired. The discharge from the valve 118 passes to waste through the 80 "roughing throttle" valve shown at 142, and thence through the pipe 143. The pressure at the approach to the orifice 116 is connected by the duct 138 to the chamber 168 and the pressure from the cell 51 is led by the duct 85 139 to the chamber 169, while the pressure of the fluid escaping from the proportional throttle is connected from the meter 121 to the chamber 167 by the pipe 151, its pressure being governed by the throttling action of 90 the valve 142 as effected by the two pressures and any desired weight such as that of the parts acting thereon to approximately maintain such functional pressure regulation as is found to meet the most favorable 95 conditions for the operation of the valve 118. The combination of the pressure difference intensifier 115, the roughing throttle apparatus in the lower right hand corner 100 of the figure, the equal pressure diaphragm 117 and the proportional throttle 118 will give substantially perfect functional regulation, but because the coefficient of discharge of different discharging members for 105 different kinds and sizes and shapes of such members is increased with velocities for some discharging members and decreased with velocities for others, but always with a rate of change which accelerates at very low velocities and becomes immaterial at moderate or very high velocities, it follows that functional flows do not necessarily mean a constant ratio of flow at all velocities and for 110 most purposes a constant ratio of flow at all velocities is what is desired.

The most simple and practical method of obtaining this desired result I have found to be by supplying a proper force in one direction acting against the equal pressure diaphragm, illustrated in this embodiment by the spring 137, in compression, which results in maintaining a pressure in the cell 51' a predetermined amount lower than the pressure in the cell 51, and therefore, a difference of pressure on the orifice 116 by 130.

that amount greater than it would be otherwise. This difference being very small still is a material factor in increasing the governed flow through the valve 118 at low velocities, but becomes an immaterial factor at high velocities, and therefore, becomes a substantially perfect corrective of a departure from constant ratio which follows a similar law whether caused by slight unbalancing action of the valve 118, due to the flow therethrough, or to diverging coefficients as between the various discharging members which are functioning together, each according to its own law.

In the lower right-hand corner of the figure there is shown means, here consisting of a plain orifice tank with two orifices, set one slightly higher than the other to divide a flow in two parts having constant ratios, the one a certain definite and constant number of times the other. For instance, the small orifices O_1 and O_2 , when the flow through them is referred to the head over their center between any range of said heads from the level A to the level B and measured by the formula

$$V = C\sqrt{2gh}$$

will show a varying value of the coefficient C with different amounts of variation for different sizes of orifices. The very small orifice O_1 will have quite a wide variation; the larger orifice O_2 will have a less amount of variation. In either case I have discovered that there is a constant amount or value, which, if it is added to h in the above formula will make the coefficient of C constant for all heads over said orifices. For instance, for orifice O_1

$$V = C_{1e}\sqrt{2g(h_1 + E_1)}$$

and for orifice O_2

$$V = C_{2e}\sqrt{2g(h_2 + E_2)}$$

will always express the discharges through said orifices and for either orifice. C_{1e} and C_{2e} and E_1 and E_2 will be constant for all heads, h_1 and h_2 , between the limits of head A and B, and if the orifices O_1 and O_2 are placed in that relative position in which h_1 and E_1 equal h_2 plus E_2 equal h_3 , it will necessarily follow that the ratio between the discharges from said orifices will be a constant ratio and the head h_3 read in the sight tube S above the arbitrary line at Q will give the total head, including both E_1 or E_2 necessary to be used for the calculation or indication of discharge of both orifices with a constant value of the coefficients C_{1e} and C_{2e} , so that the sight tube S can be graduated with a graduation for velocity in accordance with the formula

$$V = \sqrt{2gh_3}$$

which graduation will be constant for both

orifice O_1 and orifice O_2 , and the supply of water from 143 entering the tank T will be divided into proportional parts as it escapes from the orifices O_1 and O_2 , so long as such supply is sufficient to maintain a level equal to or greater than the level A in tank T and does not overflow said tank, or if said tank is closed, no matter how great the pressure in said vessel may become. E_1 and E_2 may be negative.

It will be understood that I may employ any form of "pressure difference intensifier," a number of different forms thereof being illustrated in the patent to Ferris 790,888.

I have illustrated these methods and these types of apparatus for the purpose of showing some of the uses of my invention. It will be understood that I do not wish to be limited to the particular methods and apparatus illustrated, these having been shown for the purpose of better explaining my invention. Indeed, it will be apparent to one skilled in the art that many departures may be made from the form and details illustrated, without departing from the spirit of my invention, which is set forth more particularly in the appended claims.

I claim:—

1. The method of actuating apparatus functionally to a first fluid flow, which flow is itself functional to a difference between two initial fluid pressures, which method consists in producing a separate fluid flow from the higher to the lower of said fluid pressures through a tube of venturi form and utilizing the lower pressure produced by the venturi as one of two pressures, the other of which is the higher initial pressure, to govern a flow of fluid proportional to said first flow and actuating the apparatus by said proportional flow.

2. The method of actuating apparatus proportionally to a fluid flow, which consists of by-passing a portion thereof, intensifying the difference in pressure between two points in said flow, employing such intensified pressure difference to govern a proportional flow and governing said apparatus through said proportional flow.

3. The method of actuating apparatus proportionally to a flow of fluid, which consists in by-passing a portion thereof, intensifying the pressure difference between two points in said fluid flow, governing thereby a fluid pressure functional to said intensified pressure difference and utilizing such fluid pressure to actuate apparatus.

4. The method of actuating apparatus hydraulically, functional to the difference between two fluid pressures in a fluid main, which consists in by-passing fluid flow from the higher to the lower of said fluid pressures, and intensifying or increasing the pressure difference between said two dif-

- ferent fluid pressures in said fluid main and governing another fluid pressure, thereby and through said governed pressure controlling such apparatus.
5. The method of actuating apparatus hydraulically, which consists in providing an opening through which fluid flows from a higher to a lower pressure condition, providing in parallel with said opening another opening, inserting in said second named opening a Venturi tube, providing pressure controlled means governing another pressure to control said apparatus and connecting said pressure-controlled means to the approach and the throat of said venturi, and permitting said pressure controlled means to be operated functionally to the variation of the head in said venturi.
6. In a hydraulic system, the combination of a fluid main through which fluid may flow, a source of pressure to which said main is connected, a Venturi tube of smaller cross-section than the main placed in the path of the flow of fluid from said source, apparatus responsive to variations in fluid pressure in said venturi for creating a proportional flow and ducts connected to said apparatus and to the throat of said venturi and to said fluid main to govern said proportional flow.
7. In a hydraulic system, the combination of a fluid main, a source of pressure connected to one end of said main, an outlet for discharge of fluid associated with the other end of said main, a Venturi tube of smaller cross-sectional area than the main connected in the path of the flow of fluid between said sources and said outlet, a fluid chamber and a movable division in such chamber, a duct connecting a portion of the chamber on one side of said member to the approach of said venturi and a second duct connecting a portion of said chamber on the other side of said movable member to the throat of said venturi of smaller cross-sectional area, a valve chamber and a valve in said chamber controlled by said movable member, means to convey fluid through said valve chamber and apparatus actuated by the flow of fluid through said valve chamber.
8. In a hydraulic system, the combination of a fluid main, a source of fluid pressure and supply to create a flow therethrough, means to cause two different fluid pressures to exist in the line of said main functional to the flow therethrough, a by-pass for fluid flow from the higher to the lower of said different fluid pressures, means creating a restriction in said by-pass with approach and recovery members of venturi form adapted to cause a temporary intensified reduction of pressure at said restriction below the pressures at the approach or at the recovery end of said by-pass proportional to the difference between said two last named
- pressures, and mechanism including said restriction to regulate a fluid flow proportional to the main flow.
9. In a hydraulic system, the combination of a fluid main, a main Venturi tube in said main, a source of fluid pressure associated with one end of said main venturi and an outlet for the discharge of fluid associated with said main on the other side of said main venturi, a small venturi connected between the approach and throat of the large venturi, a fluid pressure chamber, a movable member in said chamber, a duct for conveying fluid from the approach of the smaller venturi to the one side of said movable member, means controlled by said movable member for creating a flow of fluid proportional to the flow in the main and apparatus actuated by said proportional flow.
10. In a hydraulic system, the combination of a fluid main, a large venturi in said main, a small venturi connected between the approach and the throat of the large venturi, the approach and throat of the large venturi being provided with a large opening to connect to the small venturi, a pressure chamber, a movable member in said chamber, means to convey fluid pressure from the approach and throat respectively of said small venturi to opposite sides of said movable member and means controlled by said movable member creating a flow of fluid proportional to the flow in the main and apparatus controlled by said proportional flow.
11. In a fluid system, the combination of means for creating a plurality of fluid pressures, a duct through which fluid flows, a valve controlling the flow of fluid through said duct, mechanism controlling said valve governed by said fluid pressures and apparatus governed by one of said pressures for absorbing the excess fluid pressure from said valve.
12. In a fluid system, the combination of a source of initial fluid pressure and supply, a duct to conduct fluid flow therefrom, means to obtain a temporary reduction of pressure in a functional part of said flow, functional to the whole flow, and means to utilize the pressure in said duct and the pressure due to the temporary reduction in pressure to govern a fluid flow functional to the difference between such pressures including a pressure governed governing valve adapted for fine adjustment of the desired functional relation, and a corrective resistance to motion in one direction applied to said pressure governed governing valve adapted to correct for any divergence in the ratio between the governed and governing flows.
13. In a hydraulic system, the combination of a passage-way through which fluid under pressure flows, a Venturi tube connected in the path of fluid flow in the passage-way, the largest cross-sectional area of

- the venturi being smaller than the section of the passage-way where it is associated with the main, functional fluid flow regulating mechanism, including pressure cells, a movable member and a valve, means to connect said pressure cells to the approach and throat of said venturi and apparatus actuated by the functional flow created by such mechanism.
14. In a fluid pressure system, a source of initial fluid pressure and supply, fluid discharging members, means to cause a fluid flow therefrom through a plurality of said discharging members, means to cause the flow through two of said members to bear a constant ratio to one another at all rates of flow, including means to cause the total fluid pressure acting upon and causing flows through one of said discharging members through variations of said pressures to differ by a predetermined constant amount from the pressure acting upon and causing flow through the other of said discharging members.

15. In a fluid pressure system, a source of initial fluid pressure and supply, a fluid discharging member, means to cause a fluid flow therefrom through said discharging member, means to obtain a change of pressure which is functional to a difference in pressure due to the flow through said discharging member, means to obtain from said functional change of pressure another pressure which shall differ therefrom by a constant predetermined amount which amount corresponds to E in the formula herein proposed, viz.,

$$V = C\sqrt{2g(h+E)}$$

and results in a constant value of both C and E for a wide range of velocities of flow in any given discharging member.

16. In a fluid system, the combination of a source of initial fluid pressure and supply, means to cause a governing fluid flow therefrom and a change of pressure functional to said flow, means to cause a temporary reduction of pressure in a functional part of said flow greater than the aforesaid change of pressure obtained in the whole flow, and functional to the whole flow, means to utilize said initial pressure and the pressure due to said temporary reduction in pressure to govern a fluid flow functional to the difference between said pressures, including two successive pressure governed throttling valves through which said governed flow passes, the one adapted for fine adjustment of the desired functional relation, and the other as a roughing throttle to absorb excess pressure in an approximately functional relation with the pressures applied to it and means, including a corrective resistance to motion in one direction applied to the first named throttling valve adapted to modify the governed pressure, and there-

by maintain a constant ratio between the governing and governed flow.

17. In a fluid system, the combination of means for creating a plurality of fluid pressures, a duct through which fluid flows, means controlling the flow of fluid through said duct, mechanism controlling said last named means governed by said fluid pressures and apparatus governed by one of said pressures for absorbing the excess fluid pressure from said last named means.

18. In a fluid system, the combination of a source of initial fluid pressure and supply, means to cause a governing fluid flow therefrom and a change of pressure functional to said flow, means to obtain a temporary reduction of pressure in a functional part of said flow greater than the aforesaid change of pressure obtained in the whole flow and functional to the whole flow, and means to utilize said initial pressure and the pressure due to said temporary reduction in pressure to govern a fluid flow functional to the difference between such pressures including a pressure governed governing valve adapted for fine adjustment of the desired functional relation.

19. In a fluid system, the combination of a source of initial fluid pressure and supply, means to cause a governing fluid flow therefrom and a change of pressure functional to said flow, means to obtain a temporary reduction of pressure in a functional part of said flow greater than the aforesaid change of pressure obtained in the whole flow and functional to the whole flow, and means to utilize said initial pressure and the pressure due to said temporary reduction in pressure to govern a fluid flow functional to the difference between such pressures including a pressure governed governing valve adapted for fine adjustment of the desired functional relation, and a corrective resistance to motion in one direction applied to said pressure governed governing valve adapted to modify the governed pressure.

20. In a fluid system, the combination of an initial source of fluid pressure and supply, means to cause a governing fluid flow therefrom and a change of pressure functional to said flow, means to obtain a temporary reduction of pressure in a functional part of said flow greater than the aforesaid change of pressure obtained in the whole flow, and means to utilize said initial pressure and the pressure due to said temporary reduction in pressure to govern a fluid flow functional to the difference between said pressures including two pressure governed governing valves, both acted upon by pressures derived from the governed and governing flows, the one adapted for fine adjustment of the desired functional relation and the other constituting a roughing throttle to absorb excess pressure in the line of the gov.

erned flow passage-way and to maintain a pressure acting toward the valve which must make the finer pressure adjustment approximately functional to its requirements but always affording a safe margin of difference of pressure on its two sides to give to it the final and fine regulation of the governed flow.

21. In a fluid system, the combination of a source of initial fluid pressure and supply, means to cause a governing fluid flow therefrom and a change of pressure functional to said flow, means to utilize the difference between said initial pressure and said changed pressure to govern a fluid flow functional to the difference between said pressures, including a pressure governed governing valve acted upon by pressures derived from the governing and governed flows, adapted for fine adjustment of the desired functional relations, and a corrective resistance to motion in one direction applied to said pressure governed governing valve adapted to correct for any divergence in ratio between the governed and governing flows at low velocities of flow as compared with the ratio which exists at high velocities of flow.

22. In a fluid system, the combination of a source of initial pressure and supply, means to cause a governing fluid flow and a change of pressure functional to said flow, means to utilize the difference between said initial pressure and said change of pressure to govern a fluid flow functional to the difference between said pressures including two pressure governed governing valves, both acted upon by pressures derived from the governed flow and from the governing flow, the one adapted to maintain the exact functional relation desired and the other a roughing throttle to absorb a roughly functional amount of excess pressure beyond that essential for the effective operation of the first named valve.

23. In a fluid system, the combination of a source of initial pressure and supply, means to cause a governing fluid flow therefrom and a change of pressure functional to said flow, means to utilize the difference between said initial pressure and said change of pressure to govern a fluid flow functional to the difference between said pressures including two pressure governed governing valves, both acted upon by pressures derived from the governed flow and from the governing flow, the one adapted to maintain the exact functional relation desired and the other a roughing throttle to absorb a roughly functional amount of excess pressure beyond that essential for the effective operation of the first named valve, and a corrective resistance to motion in one direction applied to the said first named valve adapted to modify the difference of pressure on the governed flow as compared with the difference of pressure on the governing flow by

such small amount as may be required to maintain a constant ratio of governed flow to governing flow at both low and high velocities of flow.

24. In a fluid system, the combination of means for creating a plurality of fluid pressures, a duct through which fluid flows, a device controlling the flow of fluid through said duct, mechanism controlling said device governed by said fluid pressures and apparatus governed jointly by said fluid pressures for absorbing the excess fluid pressure from said device.

25. In a fluid system, the combination of means for creating a plurality of fluid pressures, a duct through which fluid flows, a valve controlling the flow of fluid in said duct, mechanism controlling said valve governed by said fluid pressures and a second valve in said duct controlling the flow of fluid therein on the discharge side of said first named valve governed by said fluid pressures.

26. In a fluid system, the combination of means to create a plurality of fluid pressures, a duct through which fluid flows, a valve controlling the flow of fluid through said duct, mechanism governed by said fluid pressures controlling said valve and a second valve governing the flow in said duct and controlled jointly by said pressures and the pressure in said duct on the discharge side of said first named valve.

27. In a fluid system, the combination of means to create a plurality of fluid pressures, a duct through which fluid flows, a valve in said duct governed by said fluid pressures controlling the flow of fluid through said duct, a second valve in said duct on the discharge side of the first valve and mechanism controlling the second valve including a pair of movable members, one of which is controlled by said pressures and the other by one of said pressures and the pressure in said duct on the discharge side of the first named valve.

28. In a fluid system, the combination of means in which a plurality of fluid pressures are created, a duct, the flow of fluid in which is governed by said pressures, a valve in said duct and mechanism including a pair of movable interconnected members, the movement of one of which is controlled by said pressures and the movement of the other by one of said pressures and fluid pressure in said duct.

29. In a fluid system, the combination of means in which two fluid pressures are created, a duct through which fluid flows under pressure, a valve controlling the flow of fluid in said duct and mechanism controlling said valve including a pair of interconnected movable members in a fluid chamber, one of which is controlled by said pair of pressures and the other by one of said

pair of pressures and the fluid pressure in the duct.

30. In a fluid system, the combination of means containing fluid under pressure, second means containing fluid under second and different pressure, a duct adapted to convey fluid under pressure, a valve controlling the flow of fluid through said duct, mechanism including a movable member 5 governed by said fluid pressures controlling said valve, a second valve in said duct controlling the fluid pressure in the duct, a fluid chamber associated with said second named valve, a pair of interconnected movable members connected to said second named valve and controlling the same, a pipe connecting said first named means to

one side of one of said members, a second pipe connecting the other side of said last named member and one side of the other 20 of said members to said second named means, said pipes conveying fluid pressure from said means to said members, and apparatus to convey fluid pressure in said duct to the other side of the other member. 25

31. In a fluid system, the combination of sources of fluid pressure, a fluid duct, two valves, each controlling said duct, mechanisms, one controlling each of said valves, and means to connect each mechanism with 30 each of said sources of pressure.

In witness whereof I have signed my name hereunto this 3rd day of April, 1916.

GEORGE GOODELL EARL.

It is hereby certified that in Letters Patent No. 1,311,861, granted July 29, 1919, upon the application of George Goodell Earl, of New Orleans, Louisiana, for an improvement in "Hydraulic Systems and Methods," an error appears in the printed specification requiring correction as follows: Page 3, line 60, for the word "and" read *or*; and that the said Letters Patent should be read with this correction therein that the same may conform to the record of the case in the Patent Office.

Signed and sealed this 4th day of October, A. D., 1921.

[SEAL.]

KARL FENNING,

Acting Commissioner of Patents.
